UNITED STATES PATENT OFFICE.

SAMUEL CLELAND DAVIDSON, OF BELFAST, IRELAND.

CENTRIFUGAL FAN AND PUMP.

1,105,967.

Specification of Letters Patent. Patented Aug. 4, 1914.

Application filed November 17, 1913. Serial No. 801,446.

To all whom it may concern:

Be it known that I, SAMUEL CLELAND DAVIDSON, of Sirocco Engineering Works, Belfast, Ireland, have invented certain new and useful Improvements in or Relating to 5 Centrifugal Fans and Pumps, of which the following is a specification.

This invention refers to centrifugal fans and pumps of the incased type, and relates 10 to an improved construction of the casing for further utilizing, in practical operation, the peculiar phenomena described in a previous U. S. A. application of 25th September 1912, Ser. No. 722,220, which patent is 15 hereinafter referred to as my prior patent. In my said prior patent, I have described certain phenomena, whereby when the fan is rotating within a concentric or a spiral inclosing casing of ordinary construction, the 20 air discharged from what is referred to as the "positive" ends of the fan blades, passes across, and in part reenters the fan wheel centripetally at the negative end of the blades, the central part of the blades be- 25 tween the negative and positive ends being referred to as the neutral point. In my said prior patent, means are described whereby that part of the air which enters centripetally through the negative part of the 30 blades was mainly taken from the suction side of the fan wheel, and in some of the described arrangements an additional volume of air passes by induction over the outside of the periphery of the blades, from the 35 suction side into, and combines with the air discharging from the positive end of the fan wheel, without passing directly through the fan wheel at all.

A casing made in accordance with this in- 40 vention may have that portion which lies beyond the periphery of the fan wheel of circular, curved or rectangular form in section and the edge of the casing on the suction side is turned inward over the periph- 45 ery of the blades toward the positive end of the fan wheel the terminal edge of said turned in portion forming a circle of greater diameter than that of the intake end of the fan wheel and extending if required as far 50 as the negative portion of the fan blades.

The accompanying drawings show some constructions of casing embodying the present invention.

Figure 1 is a cross section of a single in- 55 take fan. Fig. 2 is a side elevation of Fig.

1. Fig. 3 is a modification of a single in- take fan. Fig. 4 is a cross section of a dou- ble intake fan. Fig. 5 is a part sectional plan, (with fan dotted,) showing the lip or flange a^5 .

According to the modification shown in Fig. 1 the casing a is of such cross section that the part a' thereof which is contiguous to the positive end of the fan wheel, and is parallel therewith, or to the back of the fan in the case of a single intake fan, gradually curves outwardly toward the central part of the casing, and then inwardly as at a^2 over toward, and as far as (or about) the plane of the negative or intake ends n of the blades, and, in its further extension a^3 curves inward and back toward the positive end p of the fan wheel, the terminal edge a^4 of this curvature forming a circle of greater di- 70 ameter than that of the intake end b' of the fan wheel b and the said extension a^3 ex- tending more or less over the intake end of the fan wheel, but not farther than the neutral part o of the blades, which is about mid- 75 way of their axial length. An annular space c is thus left between said terminal edge and the periphery of the wheel b , through which space c an induced current of fresh air can pass as indicated by the arrows into the cas- 80 ing from the suction side, and a part of which current can enter centripetally into the spaces or ports between the negative ends of the blades as described in my prior patent, while the remainder of the induced current flows axially along the outer sur- 85 face of said negative end, and joins in, or combines with the air which is whirling around, and along the concave interior cir- 90 cumference of the casing, as well as with the fresh air which is being directly discharged from the positive end p of the fan wheel, and the induced air thus admitted adds to the volume being discharged out of the cas- 95 ing, without said induced air having to pass through the fan wheel b at all. By this im- proved construction of the inclosing casing around the fan wheel, the additional volume of air admitted by induction, so increases the total volume dealt with, that a much smaller diameter of fan wheel can be em- 100 ployed for the required duty, than if all the air had to pass through the wheel itself, but of course the velocity of discharge, or the pressure set up thereby, will only be a re- 105 sultant between that of the direct discharge 110

from the fan wheel, and the volume of induced air, which is being admitted at atmospheric pressure.

According to a second modification shown in Fig. 3 of this invention the cross sectional curvature of the casing at a^2 is carried out beyond the plane in which the intake end of the fan wheel b lies, the terminal edge a^4 of said curvature is brought around, and back to, the plane of the intake end of the fan wheel, while still having the circle c formed by said terminal edge a^4 greater than the periphery of the intake end of the wheel, to admit the induced current of fresh air from the suction side as in the first hereinbefore described modification toward the positive end p of the fan wheel and in some cases said terminal edge a^4 of the casing may project past or be within the plane of the intake end of the wheel as indicated in Fig. 5 so as to be parallel therewith all around, or only a part may be thus extended inward over the negative end of the fan, in the form of a lip or flange a^5 which may project inward past said plane to any suitable distance, not exceeding say half the length of the blades, the part a^6 of greatest projection being preferably contiguous to the discharge outlet from the casing. According to this second modification, a larger area of discharge from the casing can be obtained, without having to increase the over-all diameter of the casing, than when it is constructed in accordance with the first hereinbefore described modification.

The formation of the casing will be suitably modified in the case of a double intake fan and that portion of the casing which is coincident with the central plane of the fan wheel may be carried inward toward the fan wheel or not as may be required.

Fig. 4 shows one construction applied to double intake fan wheel the central part of the casing being provided with an inwardly projecting flange f to properly direct the current of air leaving the central positive portions p p' of the double fan wheel over toward the intake ends of the blades.

What I claim and desire to secure by Letters Patent is:—

1. A casing in which the edge of the casing on the suction side is turned inward over the periphery of the negative or intake end of the fan blades toward the positive end of the fan wheel the terminal edge of said turned in portion forming a circle of greater diameter than that of the intake end of the fan wheel and constituting the inlet or eye to the casing.

2. A casing having a part of circular or curved section disposed radially beyond the periphery of the fan wheel the edge of the casing on the suction side being turned inward over the periphery of the negative or intake end of the fan blades toward the posi-

tive end of the fan wheel the terminal edge of said turned in portion forming a circle of greater diameter than that of the intake end of the fan wheel and constituting the inlet or eye to the casing.

3. A casing for centrifugal fans and pumps having a wall which is contiguous to the positive end of the fan wheel and is approximately parallel therewith and which gradually curved outwardly toward the intake side of the casing and then inwardly over toward and approximately as far as the plane in which the negative or intake ends of the blades revolve and in its farther extension curves inward and back toward the positive end of the fan wheel, the terminal edge of this curvature forming a circle of greater diameter than that of the intake end of the fan wheel, and extending more or less over the periphery thereof, but not farther than the neutral part of the blades, which is approximately mid-way of their axial length, an annular space being left between the said terminal edge and the periphery of the wheel through which an induced current of air can pass into the casing from the suction side.

4. A casing for centrifugal fans and pumps having a wall which is contiguous to the positive end of the fan wheel and is approximately parallel therewith and which gradually curves outwardly toward the intake side of the casing said curvature of the casing being carried out beyond the plane in which the intake end of the fan wheel lies, and then inwardly over toward and approximately as far as the plane in which the negative or intake ends of the blades revolve, the terminal edge of this curvature forming a circle of greater diameter than that of the intake end of the fan wheel, and extending more or less over the periphery thereof, but not farther than the neutral part of the blades, which is approximately midway of their axial length, an annular space being left between said terminal edge and the periphery of the wheel through which an induced current of air can pass into the casing from the suction side.

5. A casing having a part of circular or curved section disposed radially beyond the periphery of the fan wheel the edge of the casing on the suction side being turned inward over the periphery of the fan blades toward the positive end of the fan wheel the terminal edge of said turned in portion forming a circle of greater diameter than that of the intake end of the fan wheel and constituting the inlet or eye to the casing said terminal edge being located partly or wholly within the plane of the intake ends of the fan blades.

6. A casing having a part of circular or curved section disposed radially beyond the

periphery of the fan wheel the edge of the casing on the suction side being turned inward over the periphery of the fan blades toward the positive end of the fan wheel and 5 extending a distance not exceeding one-half the length of the fan blades, the terminal edge of said turned in portion forming a circle of greater diameter than that of the intake end of the fan wheel and constituting

10 the inlet or eye to the casing.

7. A casing having a part of circular or curved section disposed radially beyond the periphery of the fan wheel the edge of the casing on the suction side being turned inward over the periphery of the negative or 15 intake end of the fan blades toward the positive end of the fan wheel, the terminal

edge of said turned in portion forming a circle of greater diameter than that of the intake end of the fan wheel and constituting 20 the inlet or eye to the casing part of the terminal edge of the casing is extended inward over the fan wheel in the form of a lip or flange, the part of greatest projection being preferably contiguous to the discharge 25 outlet from the casing.

In witness whereof, I have hereunto signed my name in the presence of two subscribing witnesses.

SAMUEL CLELAND DAVIDSON.
